WATER HEATER CASING

Kenneth P. Schory, Bensenville, Ill., assignor to A. O. Smith Corporation, Milwaukee, Wis., a corporation of New York

Application June 3, 1955, Serial No. 36,363

Term of patent 7 years

(Cl. D81—2)

Fig. 2

Fig. 2 is a top plan view thereof.

The sides and rear portion of the water heater are plain.

I claim:

The ornamental design for a water heater casing, as shown and described.
